ASSIGNOR TO SAID FOLGER.

SELF-INKING HAND-STAMP.

1,134,950.

Specification of Letters Patent.

Patented Apr. 6, 1915.

Application filed June 13, 1913. Serial No. 773,393.

To all whom it may concern:

Be it known that we, HARRY S. FOLGER and CASPER L. REDFIELD, citizens of the United States of America, and residents of 5 Chicago, county of Cook, and State of Illinois, have invented certain new and useful Improvements in Self-Inking Hand-Stamps, of which the following is a specification.

10 Our invention relates to self inking hand stamps and has for its object the improvements in such stamps.

In the present instance we have illustrated our invention as a self inking attachment for commercial hand stamps of a kind which has not heretofore been used with self inking devices.

15 It the accompanying drawings Figure 1 is a rear elevation of a large sized hand band stamp with a self inking attachment secured thereto; Fig. 2 is a side elevation of the same; Fig. 3 is a section on line 3—3 of Fig. 1, the upper part being broken away; and Fig. 4 is a similar section showing the 25 stamp in printing position.

The stamp proper consists of a series of type bands 10 supported in a frame 11 which has a handle 12. The bands 10 are supported above, on band wheels 13 which 30 are mounted on a shaft 14. At the lower part of the stamp the bands run over a bridge connecting the lower free ends of the frame 11. One end of this bridge is shown at 15 in Fig. 4.

35 The parts so far mentioned are simply parts of the ordinary adjustable hand band stamp well known in the trade, which does not need further description.

40 Through the lower part of the stamp is a shaft 16 which corresponds to and is parallel with shaft 14. The outer ends of the shafts 14 and 16 are guided in slots 17 and 18 in the side frames 19. Tie rods 20 secure the side frames 19 together below, while 45 collars 21, links 22 and screws 23 secure the upper ends of the frames 19 so that said frames will remain parallel and permit the stamp to rise and fall in the frames.

45 Supported in the frames 19 is a shaft 24, and on each end of this shaft is pivoted a link 25. Pivoted at 26 on each frame 19 is a link 27 which is of the same length as link 25. Pivoted to the free ends of the links 25 and 27 is a pad or pad box 28 which is 55 thus supported at each end by links. As

thus constructed the pad and its supporting links constitute a "parallel motion," in that the pad face always lies in a horizontal plane though it rises and falls in its movement about the pivots 24 and 26. It is 60 not at all necessary to the operation that the links 25 and 27 be of the same length, the only result of making one shorter than the other being to throw the pad out of level when not in contact with the type faces on 65 the bands 10. The length of the links 25 and 27 is such that when they are thrown forward as shown in Fig. 3 the pad will be directly beneath the center of the stamp as vertically guided in the frames 19, while, 70 when the links are thrown backward as shown in Fig. 4, the pad is moved to the rear far enough to clear the stamp as it moves downward to printing position.

Pivoted on the shaft 16 are links 29 which 75 have their free ends pivoted to intermediate points on the links 27. Springs 30 on the shaft 24 connect to the ends of the shaft 16 and act to raise the stamp to its upper position. The upper position is determined by 80 contact between the pad 28 and the type bands 10.

Hand pressure applied to the handle 12 moves the stamp in its frame 19, which stamp is guided by the shafts 14 and 16 in 85 the slots 17 and 18. The downward movement of the shaft 16 moves the links 29 downward, and as these links are connected to the links 27 pivoted at 26, it will be evident that the links 27 also move downward 90 from the position shown in Fig. 3. As links 29 are connected to intermediate points on the links 27 it will be evident that the free ends of the links 27 move downward more rapidly than the shaft 16. As the shaft 16 95 is fixed to the stamp and the ends of the links 27 are fixed to the pad, the first effect of moving the stamp downward from its upper position is to move the pad 28 downward still more rapidly and thus cause the 100 pad to separate from the type faces on the bands 10. As this downward movement of the pad is on the arc of a circle, the pad moves rearwardly to clear the type bands and later moves upwardly while the stamp 105 is finishing its downward stroke. Preferably the connections are such that the shaft 16 at its lowest position is slightly below the pivoting point connecting the links 27 and 29. The result of thus causing the shaft 16 110

to pass the center on the level with the pivotal connection between the links 27 and 29 is to cause the pad 28 to finish its rearward movement and reverse itself before the type 5 strike the paper. The advantage of having the shaft 16 pass the center is that the rapid movement of the pad is only at the time when it is clearing the stamp, and the total length of movement of the pad is reduced 10 to a minimum. When the hand pressure is released, the springs 30 raise the stamp until it locks itself in its upper position by contact between the pad and the type face. This self locking position will be evident 15 from inspection of Fig. 3 in which it will be seen that any movement of the stamp either upward or downward causes a more rapid movement in the same direction of the pad. As the pad is against the face of the type any further raising of the stamp 20 could come only as the result of forcing the type into the pad.

The springs 30 are connected at their inner ends to a collar 31 on the shaft 24. One 25 end of the shaft 24 is squared and has thereon an arm 32 which hooks over the edge of the frame 19 and maintains the proper tension on said springs. When it is desired to increase the tension of the springs 30 a 30 wrench is applied to the collar 31 to move the shaft, and consequently the arm 32, in a contra clockwise direction as shown in Fig. 3. When this is done the arm 32 may be removed from the squared end of the shaft 35 24 and be replaced in a different relationship thereto.

One of the links 22 has in it notches 33 and 34, and secured to the adjacent frame 19 is a dog 35 adapted to engage these 40 notches. When the stamp is moved downward a short distance from its uppermost position and the dog 35 is inserted in the notch 33, the pad and the type face are held slightly removed from each other. This removal of the pad from the type is to prevent the pad from being marked at spots by long continued contact with the type, and is just enough to accomplish this result. By 45 making this removal very slight, no material amount of dust settles on the pad when the stamp is not in use. The upper notch 34 is so located that when engaged by the dog 35 the stamp will be held close to the printing position and the pad at its position in the rear of the stamp. In this 50 position the pad is horizontal with its face exposed in a convenient position for renewing the supply of ink. The convenience with which the pad may be inked is one of 55 the advantages of this construction.

It will be observed from the foregoing description that the present stamp is distinguished from the ordinary "tumbler" by the fact that the stamp always stands up 60 right and moves directly to and from the

surface to be printed upon. In this construction the movement is much shorter than in the tumbler and is not at all dependent upon the vertical height of the stamp. The construction used is not only applicable to 70 a stamp designed completely for the purpose, but the self inking apparatus may be applied as an attachment to a commercial stamp without modifying the present construction. In the present instance the only 75 things necessary are to lengthen the shaft 14 by slipping a new one in the place of the one ordinarily used, and to insert a shaft 16 in the space otherwise unused.

The pad holding box 28 may be pivoted 80 directly to the links 25 and 27 as described but we prefer to pivot the links to a box holding bridge 36 and then slip the box into the bridge where it may be held in place by any convenient means. A pad box held 85 right side up as in this case is superior to the inverted box of the tumbler stamp in that if too much ink is placed in the box it will not run out but will lie in the box under the pad until absorbed.

What we claim is:—

1. A hand stamp of the type ordinarily inked by hand and having a frame of its own, a supplementary or outer frame in which the stamp frame is mounted, upper 95 and lower shafts extending through the stamp frame and having their ends guided in the supplementary frame, band wheels mounted upon the upper shaft, an ink pad pivoted to the supplementary frame, and 100 connections from the lower shaft to the pad support.

2. The combination with a hand stamp having type bands, band wheels and a shaft 105 on which the wheels are supported and rotated for moving the bands, of a second shaft inserted in the stamp, a frame having guides engaging the ends of the shafts, a spring supporting the stamp in elevated position in the frame, an ink pad engaging 110 the printing face of the stamp when in elevated position, and automatically operating means for removing the pad when the stamp is depressed.

3. The combination with a hand stamp 115 having type bands, type wheels and a shaft for said wheels, of a second shaft inserted in the stamp, a frame having guides for the ends of said shafts, a spring supporting the stamp in an elevated position in said frame, 120 an ink pad engaging the stamp when in elevated position, and connections from the second shaft to the pad for removing it when the stamp is depressed.

4. The combination with a hand stamp 125 having type bands, band wheels and a shaft on which the wheels are supported and rotated for moving the bands, of a second shaft inserted in the stamp, a frame engaging 130 the ends of said shafts to guide the

stamp in printing movement, an ink pad supported by the frame and normally engaging the printing face of the stamp, a spring supporting the stamp in the frame, 5 and automatically operating means for removing the pad from the stamp when the stamp is depressed to cause it to print.

5. The combination with a hand stamp having a frame, type bands and a handle by 10 which it is normally used as a hand inker, of an outer frame, a shaft forming part of the hand stamp and having its end projecting into guiding slots in the outer frame, a second shaft extending through the stamp 15 and having its ends projecting into other guiding slots in the outer frame, an ink pad pivoted to the outer frame, and a connection from the second shaft to the ink pad.

6. The combination with a hand stamp 20 having type bands, band wheels and a shaft on which the wheels are supported and rotated for moving the bands, and a frame within which said parts are contained, of an outer frame providing guides for the ends 25 of the wheel supporting shaft, an ink pad pivoted to the outer frame and arranged to engage the printing face of the stamp when said stamp is in an elevated position, a transverse shaft supported in the outer frame adjacent to the inner frame, and a stamp elevating spring mounted upon said transverse 30 shaft.

7. The combination with a hand stamp having a frame, a shaft, and band wheels 35 mounted upon the shaft, of an outer frame consisting of side plates providing slots for the reception of the ends of said shaft, a second shaft supported in said side plates and located to the rear of the stamp frame, 40 a pad carrying frame pivotally supported upon said second shaft, a stamp elevating spring also supported upon said second shaft, and connections from the stamp frame to the pad carrying frame.

45 8. A frame consisting of two metal plates

connected together by tie rods, a stamp located between the plates and guided by the outer faces of said plates, a pad pivoted to the side plates, a stamp elevating spring mounted upon a pivotal support for said 50 pad, and a pad moving link connected to the stamp body.

9. The combination with a hand stamp having a frame of its own, of an outer frame 55 consisting of plates located on opposite sides of the stamp, tie rods connecting the plates together, an ink pad pivoted to the outer frame, links pivoted to the stamp and connected to the pad, and a spring mounted upon the pivotal support for the pad and 60 operating through the links to elevate the stamp.

10. The combination with a hand stamp having a frame of its own, of an outer frame 65 consisting of plates providing vertical guiding slots, upper and lower projections on opposite sides of the stamp frame, said projections being arranged to enter said slots to guide the reciprocations of the stamp in the outer frame, a pad pivoted to the outer 70 frame, and links connecting the pad to two of said projections.

11. The combination with a hand stamp having band wheels and a shaft on which 75 said wheels are supported, of a frame consisting of plates located on opposite sides of said stamp, connections exterior to the stamp for securing the lower parts of opposite plates together, and means by which the wheel supporting shaft acts as a tie rod 80 connecting the upper parts of opposite plates together.

Signed at Chicago, Illinois, this 10th day of June 1903.
